UNITED STATES PATENT OFFICE.

SAM P. MILLER, OF NAVASOTA, TEXAS.

Crossover.

1,130,005.

Specification of Letters Patent. Patented Mar. 2, 1915.

Application filed November 1, 1913, Serial No. 738,724.

To all whom it may concern:

Be it known that I, SAM P. MILLER, citizen of the United States, residing at Navasota, in the county of Grimes and State of Texas, have invented certain new and useful Improvements in Crossovers, of which the following is a specification, reference being had to the accompanying drawings.

10 This invention relates to certain improvements in cross-overs for railways and the object of the invention is to provide a device of this general character wherein means of a novel and improved character are provided to effectually prevent a collision of trains traveling on the intersecting track ways.

15 The invention consists in the details of construction and in the combination and arrangement of the several parts whereby certain important advantages are attained and the device is rendered simpler, less expensive and otherwise more convenient and advantageous for use, all as will be hereinafter 20 more fully set forth.

25 The novel features of the invention will be carefully defined in the appended claim.

In order that my invention may be better understood, I will now proceed to describe 30 the same with reference to the accompanying drawings, wherein—

Figure 1 is a diagrammatic view of a crossover constructed in accordance with an embodiment of my invention; Fig. 2 is an enlarged sectional view illustrating the form 35 of contact employed in my invention as herein set forth; Fig. 3 is an enlarged sectional view illustrating a means for controlling a switch; and Fig. 4 is an enlarged 40 sectional view illustrating a means for operating a signal as herein embodied.

As disclosed in the accompanying drawings, 1—1 denote the intersecting track ways, each of which is provided to either 45 side of the second track way with a branch track 2 in communication with the main track line through the medium of a suitable switch 3, the construction and operation of which forming in its details no 50 particular feature of the present invention other than to state that such switch is adapted to be operated through the medium of an arm 4 under control of a double acting solenoid 5, as particularly shown in Fig. 55 3, adapted to be properly operated upon the energizing of either the windings 6 or

7, the action of the windings 6 being to adjust the switch into closed position, while the action of the windings 7 is to return the switch into open adjustment relative to the 60 main track way 1.

Coacting with the switches 3 are the signals 8, each herein shown in the form of a semaphore as generally employed in connection with railways; and each of the semaphores 8 is suitably actuated, as indicated in Fig. 4, by a double acting solenoid 9 under control of the windings 10 and 11, the windings 10 serving to cause the semaphore to be elevated when the adjacent 70 switch 3 is opened and to drop or fall when such switch 3 is adjusted into closed position.

At predetermined points on each of the main track ways 1 and to opposite sides of 75 the intersecting track way and in advance of the switches 3 are the circuit closers 12 adapted to be compressed by a suitable shoe or other means carried by the train to complete such circuits as will energize the 80 proper windings 6 and 10 whereby signal will be given by the proper semaphores 8 that a train on the second track is about to make a cross-over and to assure the passing of a train which may ignore the signal 85 onto a branch 2 whereby it will be readily perceived that the possibility of a collision is effectively and automatically guarded against. While I prefer to employ a branch 90 it is to be understood that a derailing switch may be used.

To either side of the intersecting track ways 1 and interposed between the switches 3 and the track ways 1 are the additional circuit closers 15 which are also adapted to 95 be engaged by a suitable shoe or other means carried by a train passing over either of the track ways and serving to energize the windings 7 and 11 whereby the switches are 100 adjusted to their normal positions or closed relative to the main line and the semaphores caused to drop after a train has made the cross-over. The circuit closers 15 are identical with the circuit closers 12 and may be constructed as indicated in detail Fig. 2. 105 The particular manner whereby the several circuit closers and operating means for the switches and semaphores are controlled forms no particular part of my invention as herein embodied, and it is not believed 110 to be necessary to disclose the same other than to say that such devices are suitably

connected in multiple from the source of electrical energy, as indicated at 16.

The circuit closers 12 and 15 are, as herein disclosed, substantially identical in construction and for this reason it is thought that a description of one will suffice for both. As disclosed particularly in Fig. 2, the circuit closer 12, therein illustrated, comprises the two contact members 17 and 18 in electrical connection with the source of electrical energy 16 through the conductors *a*, the contact 17 being movable relative to the contact 18 and, as herein disclosed, comprises a spring plate adapted to be engaged by the inner extremity 19 of the arm 20 pivotally supported, as at 21, intermediate of its length, the opposite end 22 thereof terminating in close proximity to a track-way 1 and adapted to be depressed by the wheels of a train passing over such track-way, as is believed to be self-evident.

From the foregoing it is thought to be obvious that a cross-over constructed in accordance with my invention is of an extremely simple and comparatively inexpensive nature and is particularly well adapted for use by reason of the effective manner in which it is caused to operate to prevent collision of trains passing over intersecting lines, and it will also be obvious that my

invention is susceptible of some change and modification without material departure from the principles and spirit thereof and for this reason I do not wish to be understood as limiting myself to the precise arrangement and formation of the several parts herein shown in carrying out my invention in practice. 35

I claim:

The combination with intersecting track ways, of branches for each of such track ways in advance of the point of intersection, a switch for controlling the communication from each of the main lines of the track ways to its branch, electrically operating means independent of the train controlled from a point on one of the main lines for actuating the switch of the intersecting train line, such electrically operating means including a normally open circuit closer positioned in close proximity to each of the main lines adapted to be closed by a train passing over such main line. 50

In testimony whereof I hereunto affix my signature in the presence of two witnesses. 55

SAM P. MILLER.
